(57) **CLAIM**

The ornamental design for a female urinary director, as shown and described herein.

DESCRIPTION

FIG. 1 is a front perspective view of a female urinary director, showing our new design;

FIG. 2 is a side perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof; and,

FIG. 9 is a side view of the female urinary director in a folded position.

The broken lines in the drawings illustrate portions of the female urinary director and form no part of the claimed design.

1 Claim, 3 Drawing Sheets
